UNITED STATES PATENT OFFICE.

ROBERT PAINE, OF WEST HOBOKEN, NEW JERSEY.

FLOATABLE FOUNDATION FOR BUILDINGS.

1,088,239.

Specification of Letters Patent. Patented Feb. 24, 1914.

Application filed March 1, 1913. Serial No. 751,502.

To all whom it may concern:

Be it known that I, ROBERT PAINE, a citizen of the United States of America, and resident of West Hoboken, in the county of 5 Hudson and State of New Jersey, have invented certain new and useful Improvements in Floatable Foundations for Buildings, of which the following is a full, clear, and exact description.

10 This invention relates to a building structure composed of concrete or artificial stone, that may be suitably reinforced and which is shaped so as to be floatable.

The present invention is an improvement 15 on the structure set forth in an application Serial No. 699,603, filed by me, wherein a similar construction is set forth.

In the present invention the foundation is formed of spaced walls thereby providing 20 one or a number of closed compartments that will increase the buoyancy of the structure; and which foundation is provided with a central floor or stage in the interior that may be surrounded by annular rows of tiers, 25 forming seats or which may be provided with chairs or benches.

In the accompanying drawing showing one embodiment of my invention: Figure 1 is a vertical section through the foundation 30 showing a superstructure thereon. Fig. 2 is a broken cross section as indicated on the line 2—2 of Fig. 1. Fig. 3 is a view substantially similar to Fig. 1 but as taken at right angles thereto, and showing a slight 35 modification in the construction of the floatable foundation.

Referring to the drawings the structure is shown as provided with a foundation composed of an outer curved or spherical wall 40 7, and an inner curved or spherical wall 8 that are shown as united at the central bottom portion 9; all of the walls or parts of the structure (or most of them) are formed of artificial stone or concrete of any desired 45 composition; and the same may be suitably reinforced in any desired manner, but the reinforcement is not shown in the drawing. These curved walls are connected at the top by a wall or portion 10 shown in the form of 50 a horizontal annular platform; and the outer portion of the lower walls 7 has a vertical extension or wall 12 of cylindrical contour, that connects with the outer portion of the platform 10. If desired a fender 55 or buffer 13 may be provided at the outer portion of the wall 10 for the purpose of

relieving any sharp blows that the structure may sustain, which fender may be constructed of wood or metal or of any desired cushioning material. The space between these walls or shells 7 and 8, including the platform 10 and the cylindrical wall 12, constitutes a closed compartment that will greatly increase the buoyancy of the structure. These walls are further strengthened 60 by a series of radial walls 14, forming a series of closed divisional compartments 32 between these partitions; that will make for safety, as should any one or a few of these compartments be punctured admitting the 65 water, the remaining ones would serve to still float the structure.

At the central interior portion of the inner shell 8 is provided a circular floor or stage 15. The inner shell between the stage 75 15 at the bottom, and the upper platform 10, may be provided with alternate treads and risers 30, thereby forming annular tiers; that may themselves constitute seats, or may have chairs or benches placed thereon, to 80 thereby constitute a kind of amphitheater.

The structure is shown provided with a top member of annular form, denoted generally by 17, that is suitably supported from the platform 10 by upright members. An 85 annular series of posts 18 are shown forming the supports for the roof 17. And an annular vertical wall 19 is provided connecting the platform and the roof, inside of the posts 18; the wall being provided with 90 doors 20 at suitable locations, such as the aisles 30'.

At one side the platform 10 has an extension 21, and above the same a similar extension is provided for the roof, thereby 95 forming a portico, that may be the entrance for the structure. It will be observed that the posts 22 at this portion extend in a vertical plane.

The roof 17 is shown as composed of an 100 upper wall 23, and an inner annular wall 24 spaced therefrom providing a compartment 25. The roof may be provided with a central opening at 26.

This foundation may constitute a floating 105 support for a structure which may be advantageously employed as a theater, studio, bath, workshop, storage or a building for other uses; the purpose of the invention being to provide a floatable foundation which 110 by reason of its cheapness of construction and durability, and the practicability of

keeping in condition and repair renders cheap or otherwise unavailable sites available for building purposes.

In Fig. 3 the foundation is shown in substance the same as Fig. 2, but having intermediate between the lower and upper partially spherical walls, a wall 28 which construction in conjunction with the radial partitions producing upper and lower series 10 of inclosed compartments,—the portion of the structure below the intermediate wall and the inclosed compartments thereabove serving as a guard and protection to the latter portion of the structure and rendering 15 the foundation entirely safe even if some portions of the lower shell become broken or perforated.

Having thus described my invention, what I claim is:

20 1. A building structure having a floatable basin shaped foundation of concrete or artificial stone formed with a plurality of spaced curved walls forming inner and outer shells, the walls being connected at the upper 25 portion by an annular horizontal platform, upright members on the platform, and a roof member carried by the upright members.

20 2. A building structure having a floatable basin shaped foundation of concrete or artificial stone formed with a plurality of spaced curved walls forming inner and outer shells, the walls being connected at the upper portion by an annular horizontal platform, upright members on the platform, a 35 roof member carried by the upright members, and a platform on the central inner part of the inner shell at its lower portion.

30 3. A building structure of concrete or artificial stone having a basin shaped foundation 40 formed with a plurality of spaced curved walls forming inner and outer shells, the walls being joined at the central portion, the shells being connected at the upper portion by an annular horizontal platform, upright members on the platform, and a roof member carried by the upright members.

40 4. A building structure of concrete or artificial stone having a basin shaped foundation 50 formed with a plurality of spaced curved walls forming inner and outer shells, the walls being joined at the central portion, the shells being connected at the upper portion by an annular horizontal platform, upright members on the platform, and a roof member carried by the upright members, said shells being connected by radial upright walls extending to the platform.

50 5. A building structure of concrete or artificial stone having a basin shaped foundation 60 formed with a plurality of spaced curved walls forming inner and outer shells, the walls being joined at the central portion, the shells being connected at the upper portion by an annular horizontal platform, up-

right members on the platform, and a roof member carried by the upright members, the roof being connected with the platform by a vertical wall of cylindrical form.

6. A building structure having a floatable 70 basin shaped foundation of concrete or artificial stone formed with a plurality of spaced curved walls forming inner and outer shells that are connected at the central portion at the base and also connected at the top portions, the top of the inner shell being provided with alternate treads and risers to 75 form tiers.

7. A building structure having a floatable 80 basin shaped foundation of concrete or artificial stone formed with a plurality of spaced curved walls forming inner and outer shells that are connected at the central portion at the base and also connected at the top portions, a stage at the central inner 85 part of the inner shell at its lower portion, the inner shell beyond the stage being provided with alternate treads and risers forming tiers.

8. A building structure having a floatable 90 basin shaped foundation of concrete or artificial stone formed with a plurality of spaced curved walls forming inner and outer shells that are connected at the central portion at the base and also connected at the top portions, a stage at the central inner 95 part of the inner shell at its lower portion, the inner shell beyond the stage being provided with alternate treads and risers forming tiers, upright members at the top of the 100 shell portions, and a roof member carried by the upright members.

9. A building structure having a floatable 105 basin shaped foundation of concrete or artificial stone formed with a plurality of spaced curved walls forming inner and outer shells, the walls being connected at the upper portion by an annular horizontal platform, upright members on the platform, a roof member carried by the upright members, the platform and the roof having registering extensions forming a portico.

10. A building structure of concrete or artificial stone formed with a plurality of spaced curved walls forming inner and outer shells that are connected at the central portion, a horizontal platform of annular shape at the top of the inner and outer shells, the outer shell having a vertical cylindrical extension connecting with the platform, a stage at the central inner part of the inner shell at its lower portion, the inner shell beyond the stage being provided with alternate treads and risers forming tiers, radial 110 walls connecting the two shells and the annular platform, an upright annular wall at the inner portion of the platform provided with doorways, a series of posts on the platform and a roof member supported on said 115 posts and adjacent walls.

11. A building structure of concrete or artificial stone formed with a plurality of spaced curved walls forming inner and outer shells, an annular horizontal platform connecting the upper portions of the shells, an upright annular wall at the inner portion of the platform provided with doorways, a series of posts on the platform and a roof member supported on said posts and adjacent walls.

12. A building structure having a floatable basin shaped foundation of concrete or artificial stone, composed of a plurality of spaced curved walls forming inner and outer shells, and which converge downwardly to a common central portion at the bottom.

13. A building structure having a floatable basin shaped foundation of concrete or artificial stone composed of a plurality of spaced curved walls forming inner and outer shells and which converge downwardly to a common central portion at the bottom, the walls being connected at the upper portion by a wall forming a horizontal platform, and radial upright walls connecting the shells, and forming compartments.

Signed by me in presence of two subscribing witnesses.
